UNITED STATES PATENT OFFICE.

EDWIN HUMAN, OF MILWAUKEE, WISCONSIN.

VEGETABLE CUTTER.

Application filed April 17, 1922. Serial No. 554,218.

To all whom it may concern:

Be it known that I, EDWIN HUMAN, a citizen of the United States, and resident of Milwaukee, in the county of Milwaukee and 5 State of Wisconsin, have invented new and useful Improvements in Vegetable Cutters, of which the following is a description, reference being had to the accompanying drawings, which are a part of this specification.

10 The invention relates to vegetable cutters.

The general object of the invention is to provide a vegetable cutter of simple construction and one capable of slicing up, grating or otherwise cutting a large quantity 15 of vegetables in a short period of time. Specifically the object of the invention is to provide a vegetable cutter in which the vegetables are fed to the cutters by gravity and are held against the cutters by means hereinafter described.

With the above and other objects in view, the invention consists in the several features hereinafter set forth and more particularly defined by claims at the conclusion hereof.

25 In the drawings: Fig. 1 is a vertical sectional view through a device embodying the invention; Fig. 2 is a section taken on the line 2—2 of Fig. 1, parts being broken away; Fig. 3 is a detail view, similar to

30 Fig. 1, showing the lower end of the device provided with a grating plate; Fig. 4 is a detail bottom view of the grating plate shown in Fig. 3; Fig. 5 is a view of a cutting blade that may be used with the device.

35 In the drawings the numeral 6 designates a cylindrical metal shell preferably having legs 7 secured thereto to form a space beneath the lower end of the shell. Near the lower end of the shell I form integral with 40 or secure to the shell a ring 8 and I mount rollers 9 on pivots secured to said ring and shell. A rotary cutting plate, hereinafter described, forms the bottom of the container and runs on said rollers, said plate being de- 45 tachably secured to the squared portion 10 of shaft 11 by a thumb-screw 12 mounted on the threaded end 13 of said shaft.

The shaft 11 is mounted in a tubular housing 14 which is secured at its upper end to a 50 transverse frame member 15 preferably detachably secured to the upper portion of the shell by thumb-screws 16 passing through the shell and bifurcations 17 of said member. A ball thrust bearing 18 is interposed 55 between the lower end of the housing and the cutting plate. The shaft 11 carries a

bevel gear 19 meshing with a bevel gear 20 on a horizontally disposed shaft 21 journaled in bearings 22 of the frame member 15. This shaft 21 may be driven by power 60 applied to a pulley 22 mounted thereon, or may be turned by hand, as by a hand-crank 23 applied to the squared end 24 of said shaft.

To feed the vegetables to the cutters, I 65 provide a pair of spiral chutes 25 winding round the tubular member 14 in opposite directions. These chutes are formed by spirally extending members 26 secured to or formed integral with the member 14 and fitting closely within the shell and having bosses 28 at their lower ends to receive bolts 29 which pass through the shell. The members 26 may be rigidly connected to the shell, but I prefer to detachably mount them 70 in the shell so that they may be readily removed from the shell on the loosening of the bolts 29 and the screws 16 for the purpose of cleaning the parts. The lower ends of these members 26 are spaced a short distance 75 above the cutting plate and have a roughened or toothed surface 30.

The cutting plates may be provided with various forms of cutters. In Figs. 1 and 2 I show a cutting plate 31 having slotted 80 portions 32 in which straight edge blades 33 are mounted. Threaded studs 34 are mounted in the plate and carry nuts 35 and 36 engageable on opposite sides of each blade adjacent the slots 37 therein. The adjustment of the nuts 35 varies the angle which the blade makes with the flat surface 38 of the plate 31. In place of a straight edge blade a blade 39 with a serrated cutting edge 40 may be used. For grating vegetables a 85 plate 41 having sector-shaped delivery slots 42 carries a cutting plate 43 which is provided with the usual toothed edge grating 90 openings 44.

With either of the forms of cutting plates 100 secured to the shaft 19 the rotation of said plate by the mechanism previously described causes vegetables, deposited in the chutes 25 and moved down said chutes by gravity, to be wedged in between the lower roughened 105 end portions 30 of the members 26 and the cutting plate, with the result that one or more of the vegetables so held is subjected to the application of the cutting blades either to be sliced by the blade 33, shredded 110 by the blades 40 or grated by the grater formed by the plate 43. The rotation of

the shaft 11 is such as to move the vegetables to the wedged position above described, that is, the vegetables fed down by one chute are wedged in between the bottom plate and the 5 bottom portion of the other chute, with the result that all of the vegetables in the chute may be completely subjected to the cutting action and the cut vegetables discharged into a pan 45 in the space below the cutting 10 device.

By using two chutes on opposite sides of the device the thrusts against the cutting blade are equalized to a great extent so that the blade will not have any tendency to tip 15 with respect to the shaft 11, and, furthermore, the capacity of the machine is greatly increased.

What I claim as my invention is:

1. In a vegetable cutter, the combination 20 of a pair of vertically disposed oppositely extending spiral feed chutes, and a revolvable member at the bottom of said chutes provided with cutters, said chutes cooperating with said member to hold the vege-

tables against said member during the cutting 25 operation.

2. In a vegetable cutter, the combination of a pair of vertically disposed oppositely extending spiral feed chutes, the lower ends of the members forming the chute having a 30 roughened portion against which the vegetables are wedged, and a revolvable member below the members forming the chute provided with cutters.

3. In a vegetable cutter, the combination 35 of a shell, a pair of vertically disposed oppositely extending spiral feed chutes including a centrally disposed shaft housing, and spiral extending members connected with said housing and fitting inside said 40 shell, means for removably securing said housing and spiral members within the shell, a rotary shaft journalled in said housing, and a revolvable member secured to said shaft and closing off the bottom of the shell and 45 provided with cutters.

In testimony whereof, I affix my signature.
EDWIN HUMAN.
